UNITED STATES PATENT OFFICE

KENLY C. BUGG, OF ST. LOUIS, MISSOURI

DISPENSER FOR NAILS, TACKS, ETC.

Application filed June 20, 1929. Serial No. 372,326.

This invention relates to dispensers for nails, tacks, etc.

An object of the invention is to provide a dispenser for nails, tacks, rivets, etc., having an elongated receptacle for receiving the nails, tacks, rivets, etc., and for moving them individually and successively to a position in which their heads are exposed and in position to be engaged manually or by a tool and withdrawn for use.

Another object of the invention is to provide a device of the type and character mentioned having an actuator controlled by a spring for pressing the nails, tacks, rivets, etc., to position for withdrawal.

Another object of the invention is to provide a device of the type and character mentioned with a loader comprising a magazine arranged to receive and to contain the nails, tacks, rivets, etc., in rows, in combination with means for controlling the discharge of the nails, tacks, rivets, etc., from said magazine into the dispenser.

Other objects will appear from the following description, reference being made to the accompanying drawings in which

Fig. 1 is an upper end elevation of the magazine.

Fig. 2 is a front elevation of the magazine or loader with a part at the front wall broken away.

Fig. 3 is a lateral side elevation of the magazine.

Fig. 3a is a lower end view of the magazine.

Fig. 4 is a rear elevation of the magazine.

Fig. 5 is an upper end elevation of the magazine with the closure therefor removed.

Fig. 6 is a front elevation of the dispenser in position to receive a load of nails, tacks, rivets, or the like, from the magazine or loader.

Fig. 7 is a side elevation of the dispenser in position to receive a load from the magazine or loader.

Fig. 8 is a sectional view of a portion of the end of the dispenser receiving a load from the magazine or loader, the front wall of the magazine being broken away.

Fig. 9 is an upper end view of the dis-

penser, the bracket for supporting the actuating spring being in section.

Fig. 10 shows sectional views of the spring barrel or drum confining the spring of the actuator.

Fig. 11 is a front side elevation of the dispenser, with a part thereof in section, attached to an arm band whereby the device may be secured on the arm of the user.

Fig. 12 is a side elevation of the dispenser, a portion of the guide for the actuator being broken away.

Fig. 13 is a cross sectional view on the line 13-13 of Fig. 12.

Fig. 14 is a sectional view of the discharge end of the dispenser.

The magazine or loader comprises one or more tubes adapted to receive and contain the stems or shanks of nails, tacks, rivets, etc.; each tube has a radial slot through which the stems or shanks of the nails, tacks, rivets, etc., extend and through which the heads cannot pass. Accordingly, the nails, tacks, rivets, etc., may be moved along the tubes and along the slots, the heads being on the outer sides of the tubes and the stems or shanks extending through said slots and into the tubes. Means is provided in connection with the tube or tubes to guide the fasteners comprising the nails, tacks, rivets, etc., along the tubes toward the discharge end and to prevent these fasteners from dropping out except as desired, and through the discharge end of the device.

In the embodiment shown the magazine or loader comprises an elongated body 1 having longitudinally therein two tubes 2 designed and adapted to receive the stems or shanks of the fasteners. From each of the tubes 2 there is a longitudinal slot 3 through which the stems or shanks of the fasteners extend so that the heads of the fasteners contact and abut against the walls of the body 1 at the sides of the slots 3. The body 1 has a longitudinal raised portion 4 between the slots 3 and spaced therefrom a sufficient distance so that said raised portion will not interfere with the heads of the fasteners nor prevent free longitudinal movement of the fasteners along the device from the loading end to the

discharge end. A plate 5 is fastened to the raised portion 4 by removable screws 6 which permit the plate to be removed and replaced as desired. The upper end of this magazine or loader is equipped with a removable closure for the ends of the tubes 2, the same comprising a plate 7 arranged to be seated across the ends of the tubes 2 and having its ends 8 bent downwardly to engage against the sides of the body 1. A screw 9 is mounted in the upper end of the body 1 and the plate 7 has therethrough a hole 10 of sufficient size to permit the head of the screw 9 to pass freely therethrough in order to attach and remove said plate. A radial slot from the hole 10 permits lateral sliding movements of said plate so that when the screw 9 is received in the radial slot the plate 7 will be held in position. On its outer edge the plate 7 has a handle or finger button 11 whereby the plate may be freely manipulated; and on its inner edge said plate is formed with a lip 12 constituting an abutment to engage against the inner side of the body 1 and limit extent of outward movement of the plate. The abutment 12 permits the plate to move outwardly to a position in which the hole 10 is opposite the head of the screw 9 so that the plate may then be lifted from the end of the device to permit the device to be loaded or unloaded as desired.

For each tube 2 a holder or abutment for supporting the fasteners in said tubes is provided. Two of such tubes being shown, there are two levers 13 pivoted on brackets 14 attached to the sides of the body 1 by removable screws 15. The lower end of each of these levers 13 has attached thereto a pin 16 and these pins project into the space between the lateral edges of the plate 5 and the adjacent surface of the body 1. These pins project across the planes of the slots 3 in position to engage the heads of the lowermost fasteners contained in the device so as to support in said device the series of fasteners contained therein. A leaf spring 17 is provided for each of the levers 13, said springs being attached to the sides of the body 1 by removable screws 18 and having their free ends extending against the inner sides of the upper ends of the levers 13. Thus, the levers 13 are actuated to and yieldingly held by said springs 17 in position to support the fasteners in the magazine or loader. By pressing the upper ends of the levers 13 toward the sides of the body 1 in opposition to the springs 17, the pins 16 may be removed from the part of the heads of the fasteners so as to permit the fasteners to move and discharge from the magazine or loader.

A chuck or gage for the receiving end of the dispenser is provided in connection with the lower end of this magazine, the same comprising a block 19 secured to the end of the body 1 by removable screws 20 and hav-

ing notches 21 to receive fittingly the end of the dispenser. This block 19 is across the rear portion of the end of the body 1 so that the notches 21 open toward the front and toward said notches in order to receive the rear side of the end portion of the dispenser. A block 22 secured across the front of the lower end of the plate 5 by a removable screw 23 projects below the lower end of said plate and constitutes a part of the chuck or gage for locating the dispenser in position to be loaded. The block 22 has a beveled rear edge 24 to facilitate and expedite the insertion of the end of the dispenser in the chuck in position to receive a load of fasteners from the magazine or loader.

This magazine or loader may be carried by the user if desired, or may be mounted in any appropriate location. Where the device is to be carried by the user the body 1 may be formed with a pair of loops 25 near its upper end and a like pair of loops 26 near its lower end to receive belts 27 that may be fastened around the waist of the user so as to support the magazine or loader in convenient position for use to load the dispenser.

The dispenser shown comprises an elongated tube 28 designed, adapted and arranged to receive and contain the stems or shanks of the fasteners and having a longitudinal slot 29 through which said stems or shanks may extend. Like the slots 3, the slot 29 will not permit the passage of the heads of the fasteners. This construction supports the fasteners in position in which the heads are on the outside of the tube 28 and in which the stems or shanks of the fasteners extend through the slot 29 and into said tube. A plate 30 is attached to the tube 28 by removable screws 31 and has its inner edge spaced outwardly beyond the opening from the slot 29 so that the heads of the fasteners are between the plate 30 and the tube 28. This prevents the fasteners from dropping out of the device and guides them properly toward the discharge end. The lower end of the laterally extended portion of the plate 30 terminates short of the lower end of the tube 28 and has a beveled surface 32.

A bracket 33 is attached to the plate 30 by removable screws 34. An arm 35 is mounted on a pivot 36 in connection with the bracket 33 and has at its lower end a laterally extended portion 37 designed and arranged to extend across the lower end of the tube 28 so as to close said tube 28 and prevent the fasteners from dropping from the end of said tube. This laterally extended arm 37 has therein a notch 38 to receive the stems or shanks of the fasteners successively as the fasteners come into contact with said arm. The space between the arm 37 and the lower end of the plate 30 is sufficient to permit outward movement of the heads of the fasteners

one at a time. The arm 35 may be turned on the pivot 36 in a direction to move the arm 37 beyond the front of the tube 28 so as to permit the lower end of said tube to be inserted in the chuck or gage notches 21 in position to receive a load of fasteners from the magazine or loader. After the dispenser is loaded and removed from the magazine or loader the arm 35 is returned to its operative or effective position in which the arm 37 is across the end of the tube 28 and supports the fasteners in said tube.

This dispenser may also comprise an actuator or impeller for the fasteners. In the embodiment shown a block 39 is mounted for sliding movements along a rail 40 in connection with one side of the tube 28. This rail may be defined as shown (Fig. 13) by forming a longitudinal groove 41 along and in one side of the tube 28. The block 39 has on its inner edge a flange 42 extending into the slot 29 so as to engage against the head of the uppermost fastener. A cord 43 has one end attached to the block 39. This cord passes over a roller 44 near the lower or discharge end of the tube 28 and thence over a roller 45 near the opposite end of said tube to connection with a rotary spring drum or barrel 46. The spring drum or barrel 46 is rotative on a spindle 47 and encloses a clock spring 48 which has one end fastened to the drum or barrel and the opposite end fastened to the spindle 47. The power and energy of this spring 48 is utilized to rotate the drum or barrel 46 in a direction to move the block 39 along the rail 40 so as to actuate or impel the fasteners 49 toward the discharge end of the dispenser. As shown, the fasteners 49 are of that type comprising elongated stems having circumferential heads. The discharge end of the dispenser is the end across which the arm 37 extends. When the block 39 is moved along the rail 40 toward the drum or barrel 46 said barrel is rotated by the cord 43 and the spring 48 is thereby rewound and re-energized. It is necessary to move the block 39 toward the drum or barrel 46 when the dispenser is being loaded or is receiving a load from the magazine or loader. The block 39 has a projection 50 which constitutes a finger hold or handle whereby said block may be moved toward the spring drum or barrel 46.

The spindle 47 is mounted in a bracket 51 which is attached to the end of the tube 28 by a removable screw 52 (Fig. 9). This bracket constitutes an abutment to limit extent of movement of the block 39 toward the drum or barrel 46 and stops said block 39 in position in which a spring latch 53 is engaged in a notch or seat 54 in the adjacent edge of said block 39. Thus, the spring 53 will hold the block 39 in its retracted position. The spring 53 is bent or looped and projects laterally beyond the surface of the

plate 30 so that said spring may be easily manipulated and disengaged from the notch 54 so as to permit said block 39 to be moved under the impulse of the spring 48. The spring 53 is attached to the bracket 51 by a removable screw 55 so that said spring may be readily removed and replaced.

Some workmen desire to attach the dispenser to the forearm. If a workman is right-handed the dispenser is attached to the left forearm, or if the workman is left-handed the dispenser is attached to the right forearm. That is to say, in any case the dispenser is attached to the forearm which is not used by the workman in welding or operating the hammer or driver by which the fasteners are driven to or placed in effective position. In Figs. 11 and 12 I have shown an arm band 56 attached to a bracket 57 removably secured to the tube 28 by fasteners 58 and equipped on one edge with buckles 59 and on the other edge with straps 60 adapted to be engaged with the buckles to fasten the device on the forearm as stated. The device is fastened to the forearm in a position and relationship in which the discharge end of the device is downward or toward the hand and in which the guide plate 30 and the discharge opening at the beveled end 32 thereof are toward the front. In such position the head of one of the fasteners 49 is always exposed beyond the beveled end 32 of the plate 30 so that the fastener may be withdrawn laterally without any interference other than the frictional engagement of the next adjacent fastener under pressure of the block 39.

In use, the tubes 2 of the magazine or loader are loaded with fasteners in a relationship in which the downward edge of the head of each fastener extends over the upper edge of the next adjacent fastener, as will be understood by reference to Fig. 8. The tubes 2 may be filled or loaded with fasteners having stems of less length than the diameter of the tubes or of considerably greater diameter or of any intermediate lengths as desired. For, when the stems of the fasteners are of greater length than the diameter of the tubes said stems will assume inclined positions and the pointed ends of the stems of the fasteners will wipe along the inner sides of the tubes 2. These fasteners will be held in the loader or magazine by the abutments 16.

When it is desired to load or charge the dispenser the arm 35 is turned on the pivot 36 to move the part 37 toward the front beyond the plate 30, leaving the end of the tube 28 open. The end of the tube 28 is then placed in one of the notches 21 of the chuck or gage 19. In this relationship the slot 29 is in alignment with and in continuation of the adjacent slot 3 and the opening in the tube 28 is in continuation of and in alignment

with the adjacent tube 2. Then, the lever 13 is operated to withdraw the abutment 16, as shown in Fig. 8. When the abutment 16 is thus withdrawn the fasteners 49 slide downwardly from the magazine or loader into the dispenser tube 28. During this loading operation the block 39 is latched in its retracted position by the spring 53. After the tube 28 is filled or loaded with fasteners the lever 13 is released, whereupon the spring 17 operates said lever 13 to move the abutment 16 below the fasteners in the magazine or loader. Then, the dispenser is removed from the chuck or gage 19 and the arm 35 is moved to position in which the part 17 is across and closes the end of the tube 28. Because of the relationship of the fasteners in the magazine or loader, these fasteners in the tube 28 are located in position so that the lower edge of the head of each fastener is under the upper edge of the head of the next lower fastener, as will be understood by reference to Fig. 14. Then, the spring 53 is disengaged from the notch 54 in the block 39, permitting the spring 48 to control the cord 43 and press the flange 42 against the uppermost fastener 49. Thus, one of the fasteners is always yieldingly held in the notch 38, and has its head below the beveled end 32 of the plate 30.

If the workman is using a magnetized tool the fasteners may be successively and rapidly withdrawn longitudinally in the direction of their heads by placing the end or head of the magnetized tool against the head of the exposed fastener 49 below the beveled end 32 of the plate 30 and then withdrawing the tool. Or, the workman may readily remove the fasteners longitudinally in the direction of their heads by use of his fingers. In either case the workman is supplied with individual fasteners at much greater speed than he can be supplied otherwise.

From the foregoing it is now apparent that my invention is a highly useful and simplified device comprising a dispenser and a loader therefor whereby the workman is supplied with these fasteners at much greater speed and convenience than in cases where the workman carries the fasteners in a pocket or other receptacle, for instance. The construction, arrangement and relationship of the parts comprising the invention may be widely varied without departure from the nature and principle thereof. I do not restrict myself unessentially in any particular, but what I claim and desire to secure by Letters Patent is:—

1. A device of the character described comprising a slotted tube, means for supporting headed fasteners in connection with said tube in a relationship in which the stems of the fasteners are enclosed in the tube and the heads are on the outside of the tube, an element preventing the fasteners from dropping

out of the tube and terminating short of the end of the tube to leave the heads of the fasteners exposed at the end of the tube, an actuator for moving the fasteners along the tube, a wall across the end of said slot in position to be engaged by and support the heads of said fasteners, a guide for said actuator, a connection for moving said actuator, and a device for operating said connection.

2. A device of the character described comprising a slotted tube, means for supporting fasteners in said tube, an element preventing the fasteners from dropping out of the tube and terminating short of the end of the tube to expose the fasteners at the end of the tube, an actuator for moving the fasteners along the tube, a wall across the end of said slot in position to be engaged by and support the heads of said fasteners, a guide for said actuator, a connection for moving said actuator, means for operating said connection to move said actuator in one direction, and an engageable portion in connection with said actuator for moving said actuator in the opposite direction.

3. A device of the character described comprising a slotted tube for supporting fasteners, a device for preventing the fasteners from dropping out of the tube laterally, and an element pivotally supported by said tube and movable to position to extend across the end of the tube to support the fasteners in the tube and being spaced from said device a distance sufficient to permit withdrawal of the fasteners laterally from said tube.

4. A device of the character described comprising a tube having a longitudinal slot permitting the stems of fasteners to extend into the tube and the heads of the fasteners to remain on the outside of the tube, a device for holding the fasteners from dropping laterally from the tube, and an element pivotally supported by the tube and extending across the end of the tube to prevent the fasteners from dropping longitudinally from the tube and being spaced from said device a distance sufficient to permit lateral withdrawal of the fasteners from said tube.

5. A device of the character described comprising a tube having a longitudinal slot permitting the stems of fasteners to extend into the tube and the heads of the fasteners to remain on the outside of the tube, a device for holding the fasteners from dropping laterally from the tube, an element pivotally supported by the tube and extending across the end of the tube to prevent the fasteners from dropping longitudinally from the tube and being spaced from said device a distance sufficient to permit lateral withdrawal of the fasteners from said tube, and an actuator for moving the fasteners along the tube toward said element.

6. A device of the character described comprising a slotted tube for supporting fasten-

ers and having an open end, a device preventing the fasteners from dropping laterally from said tube, an element pivotally supported by said tube for closing said open end and being movable from said open end to open the end of the tube and being spaced from said device a sufficient distance to permit lateral withdrawal of the fasteners that are against said element, and means for moving the fasteners along the tube toward said element.

7. A device of the character described comprising a tube having a slot for supporting fasteners, a device preventing the fasteners from dropping laterally from said tube through said slot, an element for closing the end of said slot and supporting the fasteners in said slot, and means pivotally supporting said element for movement from said slot to open the end of the slot through said tube.

8. A device of the character described comprising a tube having a slot for supporting fasteners, a plate attached to and spaced from said tube opposite said slot preventing the fasteners from dropping laterally from said tube through said slot, an element for closing the end of said slot and being movable from said slot to open the end of the slot through said tube, means forming a space through which the fasteners may be withdrawn between the end of said plate and said element, an actuator extending between said plate and said tube and into said slot, and means for operating said actuator to move the fasteners along said slot toward said element.

9. A device of the character described comprising a tube having a slot for supporting fasteners, a plate attached to said tube at one side of said slot and having a portion extending across the plane of and spaced from the opening from said slot, a rail supported at one side of said tube, a block mounted for sliding movements along said rail and extending into the space between said plate and said tube and into said slot, a flexible connection attached to said block, a support for said connection near one end of said tube, and means near the opposite end of said tube for operating said connection to move said block along said rail.

10. A device of the character described comprising a tube having a slot for supporting fasteners, a rail along one side of said tube, a block mounted for sliding movements along said rail and extending into said slot, a plate detachably secured to said tube holding said block in the position aforesaid and preventing the fasteners from dropping laterally from said tube, means supported by said tube for moving said block along said tube, and a handle attached to said block whereby said block may be moved in the opposite direction in opposition to said means.

KENLY C. BUGG.
